INTERNAL COMBUSTION ENGINE

Jesse G. Vincent, Detroit, Mich., assignor to
Packard Motor Car Company, Detroit, Mich.,
a corporation of Michigan

Application January 19, 1931. Serial No. 509,674

13 Claims. (Cl. 123—195)

This invention relates to internal combustion engines and more particularly to engines of the Diesel type.

An object of this invention is to provide a novel and improved drive mechanism for a plurality of Diesel engine elements.

Another object of my invention is to provide a driving unit for a plurality of devices associated with an engine which can be readily attached and 10 detached from the crank case.

A further object of the invention is to provide a plural drive and housing for elements of a Diesel engine which can be utilized for application to either side of an engine so that two types 15 of devices will not be required for use with engines disposed on two sides of a boat, for example, where it is desirable to have such mechanism on adjacent sides.

Other objects of the invention will appear from 20 the following description, taken in connection with the drawings, which form a part of this specification, and in which:

Fig. 1 is a top plan view of an engine with which the invention is associated;

Fig. 2 is a side elevation of the same;

Fig. 3 is a vertical sectional view of the unitary driving mechanism taken on line 3—3 of Fig. 4;

Fig. 4 is a horizontal sectional view of the unitary driving mechanism taken on line 4—4 of 30 Fig. 3;

Fig. 5 is another sectional view taken on line 5—5 of Fig. 3.

Referring now to the drawings by characters of reference, 10 indicates the crank case and 11 the bottom cover or pan of a Diesel type of in-line engine through which the conventional crank shaft extends longitudinally. A multi-cylinder block 12 is secured upon the crank case, and side cover plates 13 extend between the head cover 40 14 and the crank case in spaced relation from the sides of the cylinder block.

The crank case 15 at one end of the cylinder block is enlarged, and secured to one wall thereof by the bolts 16 is a casing 17 for supporting and 45 carrying the compressed air distributor, the fuel oil pump and the tachometer. The attached end of the casing is formed with a central bearing 18 while the opposite end of the casing has a bearing 19 detachably associated therewith. A 50 drive shaft 20 having spaced helical gears 21 fixed thereon is carried by the bearings in the casing, such shaft being removable endwise from the casing when the bearing 19 is detached. The drive shaft extends into the crank case and is 55 provided with a gear 22 which is driven by gearing

in the crank case (not shown) actuated by the crank shaft or some other rotating engine element.

The casing extends parallel with one side of the crank case and is formed with similar parallel top and bottom walls having aligned openings 23 therein. The casing with the drive shaft therein can be assembled with the crank case so that either the top or bottom wall is uppermost, and therefore it can be applied equally well to either the right or left side of an engine. This arrangement is an advantage when a pair of engines are employed and related so that the mechanisms must be arranged on adjacent sides of engines, for example with a pair of boat engines where the apparatus is located on the inner sides thereof, because otherwise two casings of different form would be required.

A removable cap or plate 24 is secured over each of the openings 23 in the under wall of the casing by bolts 25 and bearings 26 extend therefrom into the interior of the casing. Removable cap members 27, 28 and 29 are secured over the openings in the upper wall of the casing by bolts and are provided with hollow bearing 75 portions 30 which extend into the casing and align with the bearings 26. Stub shafts 31, 32 and 33 are carried by the aligned bearings and extend exteriorly of the cap members 27, 28 and 29, while a helical gear 34 is fixed upon each 80 stub shaft in a relation to mesh with the gears 21 on the drive shaft. Screwed upon the cap 85 27 is a tachometer casing 35 and the shaft 31 is associated to drive the revolution counting mechanism therein in the conventional manner.

A pump casing 36 is mounted upon the cap 28, and the stub shaft 32 extends into the casing for driving a conventional gear pump (not shown). This pump is connected with a source of oil supply by the conduit 37 and to the manifolds 38 on each side of the cylinders by the conduit 39. The manifolds 38 have a common overflow conduit 40 associated therewith for conducting excess fuel oil back to the source of supply. Fuel injection devices 47 are associated 90 with opposite sides of each cylinder to project fuel charges into the combustion chambers and are connected with the manifolds 38.

The cap 29 forms one section of a compressed air distributing casing and associated therewith to complete the casing is a housing 41. A conduit 42 leads into the housing and is connected with a suitable source of compressed air (not shown) which can be admitted to the distributor when the engine is being turned over 105 110

for starting. The stub shaft 33 extends into the distributor chamber and has fixed thereto a distributor plate 43 which is adapted to rotate just above a plurality of passages 44 leading one to each cylinder through the conduits 45. The plate is formed with an opening 46 which rotates over the passage openings so that compressed air charges will be released through the conduits to the cylinders in their firing order 10 from the chamber into which the conduit 42 leads.

The tachometer, pump and distributor devices are detachable from the casing and can be assembled upon the caps 27, 28 and 29 and 15 attached therewith to either wall of the casing. The caps or closures 24 are arranged to be secured to either wall of the casing. The entire assembly of the casing and the units detachably secured thereto can be detached from the crank 20 case by removal of the bolts 16, the conduits associated with the pump and distributor, and the electric wiring associated with the tachometer.

The inner end of the distributor cap member 29 is formed with a flange 50 so that oil will 25 be collected therein, and passages 51 establish communication between the collected oil and the shaft 33. The shaft is formed with a spiral recess 52 which will move oil from the passages along the entire length of the shaft bearing 53. 30 The bearings for the other stub shafts 31 and 32 can be lubricated in the same manner as the bearing 53 if desired.

It will be seen that the device described can be associated with either side of an engine 35 through the rearrangement of the parts. The device, furthermore, is simple in design, provides a compact arrangement and is readily detachable as an entire unit from the crank case or as subunits from the casing.

40 While I have herein described in some detail a specific embodiment of my invention, which I deem to be new and advantageous and may specifically claim, I do not desire it to be understood that my invention is limited to the exact 45 details of the construction, as it will be apparent that changes may be made therein without departing from the spirit or scope of my invention.

What I claim is:

1. In an internal combustion engine, a crank 50 case, a casing secured to the crank case, a drive shaft mounted within and detachable with the casing, a plurality of devices detachably fixed upon said casing, and individual driving means between the devices and the drive shaft.

55 2. In an internal combustion engine, a crank case, a casing secured to the crank case, a drive shaft mounted within and detachable with the casing having a plurality of gears thereon, a plurality of devices detachably fixed upon one 60 side of said casing, and driving means between said gears and said devices carried by said casing.

3. In an internal combustion engine, a crank 65 case, a casing secured to the crank case, a drive shaft carried within and mounted on the casing, a plurality of stub shafts extending through a wall of the casing perpendicular to the drive shaft, gear means between each stub shaft and the drive shaft, and a plurality of devices fixed 70 to one side of the casing and driven by said stub shafts.

4. In an internal combustion engine, a crank 75 case, a casing secured to the crank case, a drive shaft within the casing, a plurality of stub shafts extending through a wall of the casing perpen-

dicular to the drive shaft, detachable spaced bearing members for the stub shafts fixed to the opposite walls of the casing, gear means between each stub shaft and the drive shaft, and a plurality of engine accessory devices secured to a wall of the casing and associated to be driven by said stub shafts.

5. In an internal combustion engine, a crank 80 case, a casing detachably secured at one end to the crank case, said casing having a pair of parallel walls with aligned openings therein, a drive shaft carried in the casing and having one end extending through the attached end of the casing, means in the crank shaft for driving the end of the drive shaft extending through the casing end, bearing members detachably fixed to the parallel walls of the casing and extending through the openings therein, stub shafts mounted in the aligned bearing members and projecting through the uppermost wall and the bearings associated therewith, said casing being adapted to be fixed to the crank case with either of the parallel walls uppermost, gear means between the drive shaft and the stub shafts, and a plurality of devices detachably fixed to the 90 uppermost of the parallel casing walls and associated to be driven by the stub shafts.

6. In an internal combustion engine, a crank 95 case, a casing detachably secured at one end to the crank case and having a pair of parallel walls with aligned openings therein, said casing being adapted to be fixed to the crank case with either of said parallel walls uppermost, bearing members detachably secured to the parallel walls and closing and extending through the openings 100 therein, the bearing members being adapted to be associated with either parallel wall and those applied to the upper wall being open, stub shafts carried by said bearing members and extending through those uppermost, gear means between 105 the drive shaft and the stub shafts, and engine devices carried by the uppermost bearing members and associated to be driven by the stub shafts.

7. In an internal combustion engine, a crank 110 case, a casing detachably secured at one end to the crank case and having a pair of parallel walls with aligned openings therein, said casing being adapted to be fixed to the crank case with either of said parallel walls uppermost, bearing members detachably secured to the parallel walls and closing and extending through the openings 115 therein, the bearing members being adapted to be associated with either parallel wall and those applied to the upper wall being open, stub shafts carried by said bearing members and extending through those uppermost, gear means between 120 the drive shaft and the stub shafts, and engine devices carried by the uppermost bearing members and associated to be driven by the stub shafts.

8. In an internal combustion engine, a crank 125 case, a casing detachably secured to the crank case, said casing having two opposite walls with aligned openings therethrough, either of said walls being adapted to be uppermost, a drive shaft in the casing, helical gears fixed on the shaft in 130 line with the openings in the casing walls, stub shafts extending perpendicularly to the drive shaft and at one side thereof, said stub shafts extending through the uppermost of the walls, bearing members detachably secured to the walls adjacent 135 the openings and supporting the stub shafts, said bearing members being interchangeable, helical gears on the stub shafts meshing with the gears on the drive shaft, and engine accessory devices carried by the upper wall of the casing and associated to be driven by the stub shafts.

9. In an internal combustion engine, a unitary 140 detachable structure comprising a casing, a drive shaft carried in the casing, a plurality of stub shafts carried in the casing and operatively associated with the drive shaft, bearing members for the stub shafts removably associated with said casing, and a plurality of engine accessory devices carried by said casing and driven by said stub shafts.

10. In an internal combustion engine, a crank 145 case, a casing detachably secured to the crank case, a drive shaft mounted in the casing, a plurality of stub shafts operatively associated with the drive shaft and extending through a wall of the casing and

- the casing, interchangeable bearing members for the stub shafts secured to the casing, and a plurality of engine accessory devices detachably carried by the casing and driven by said stub shafts.
- 5 10. In an internal combustion engine, a detachable unitary structure comprising a casing, a drive shaft carried in the casing, a plurality of bearing members secured to the casing, a plurality of detachable stub shafts mounted in the bearing members and operatively associated with the drive shaft, and a plurality of engine accessory devices carried by the casing and driven by said stub shafts.
- 10 11. In an internal combustion engine, a detachable unitary structure comprising a casing, a drive shaft carried in the casing, aligned detachable bearings secured to opposite walls of the casing, stub shafts carried by the bearings, gear means fixed to the stub shafts intermediate the bearings and operatively associated with said drive shaft, and accessory devices detachably mounted on the casing and driven by the stub shafts.
- 15 12. In an internal combustion engine, a crank case, a casing secured to the crank case, a drive shaft removably mounted in the casing, and a plurality of devices carried by the casing and actuated by the drive shaft.
13. In an internal combustion engine, a crank case, a casing detachably secured to the crank case, a drive shaft mounted in the casing, a stub shaft operatively associated with the drive shaft, aligned detachable bearing members secured to the casing to support the stub shaft, and an engine accessory device detachably mounted on a bearing and driven by a stub shaft.
